UNITED STATES PATENT OFFICE.

ROBERT BUTTERWORTH, OF SOMERVILLE, ASSIGNOR, BY MESNE ASSIGNMENTS, TO THE FIBERLENE COLLAR COMPANY, OF WORCESTER, MASS.

DIE.

SPECIFICATION forming part of Letters Patent No. 340,976, dated May 4, 1886.

Application filed June 6, 1885. Serial No. 167,847. (No model.)

To all whom it may concern:

Be it known that I, ROBERT BUTTERWORTH, of Somerville, in the county of Middlesex, State of Massachusetts, have invented a certain new and useful Improvement in Dies, of which the following is a description sufficiently full, clear, and exact to enable any person skilled in the art or science to which said invention appertains to make and use the same, reference being had to the accompanying drawings, forming part of this specification, in which—

Figure 1 is a diagram showing the method of cutting the collars; Fig. 2, a plan view of the under side of the upper die or force; Fig. 3, a vertical transverse section of the same, taken on line $\alpha\alpha$ in Fig. 2; Fig. 4, a plan view of the lower or bed die; Fig. 5, a vertical transverse section of the same, taken on line $\gamma\gamma$ in Fig. 4.

Like letters of reference indicate corresponding parts in the different figures of the drawings.

My improvement relates more especially to that class of dies which are employed in cutting paper and cloth-faced paper collars; and it consists in a novel construction and arrangement of the parts, as hereinafter more fully set forth and claimed, the object being to produce a more effective device of this character for certain kinds of work than was in ordinary use prior to my invention.

The nature and operation of the improvement will be readily understood by all conversant with such matters from the following explanation.

In the drawings, A represents the upper die or force; B, the stock or holder for the same; C, the lower die, and D the bed for the same.

The lower die, C, consists, in part, of two dies, $m m$, which correspond approximately in form or outline with the adjacent sections or halves of two collars placed end to end, and are attached to the bed D by screws a , the cutting-edge of each of these dies extending from v to i , and thence to z . Each of the dies m is also provided with a creaser, b , for creasing or indenting the collar on its folding-line in the usual manner; also with an embosser, d , for producing imitation stitches around the flap, and with holes $r r$, for receiving correspond-

ing punches on the upper die for punching the button-holes in the ends of the band. A clearer, f , provided with two downwardly-projecting studs, (not shown,) which work in corresponding holes in the bed D, is disposed adjoining the cutting-edges z , the clearer being provided with suitable springs, g , for raising it after being depressed by the upper die.

The embossers d and creasers b are flush or on the same plane with the cutting-edges $z i$ and clearer f , all of these parts being elevated above the bed D about three-fourths of an inch.

A die, t , provided with a hole, w , for receiving a corresponding punch on the upper die, is secured to the bed D, opposite the center of the clearer f , for punching the button-hole in the back of the collar-band. There is also an auxiliary die, j , secured to the bed D by screws 14 near its right-hand end, said auxiliary die being adapted to work in conjunction with a corresponding die secured to the holder B, for trimming the collars, as hereinafter described.

The upper die, A, consists in part of the die h , die k , embossers $l l$, creasers $n n$, auxiliary die p , and punches $e e q$. The die h is secured to the stock B by screws 20, and provided with a cutter, $s s$, corresponding with the cutters $z z$ of the lower die. The die k is provided with a cutter, u , at either side, which extends to the cutter s , the cutter u corresponding with the cutters $v i$ of the lower die. The embossers $l l$ and creasers $n n$ of the upper die respectively correspond with the embossers $d d$ and creasers $b b$ of the lower die, and are secured to plates 22, attached to the stock B by screws 24. The punches $e e$ are adapted to enter the holes r in the lower die, and are designed for punching the button-holes in the ends of the collar-band, the punch q being adapted to enter the hole w in the die t , and designed for punching the button-hole in the back or center of the collar-band, all of said punches being secured to the holder B.

Projecting from the face of the die k , near its front, there is a cutter, 25, adapted to fit a slot, 27, formed in the inner edge of the clearer f , said clearer subserving as a bed-die for said cutter.

The dies are designed to be used in cutting

collars from the side of a sheet or strip of paper or cloth-faced paper, E, one-half each of two adjoining collars being formed at the same time, as shown at H J in Fig. 1, the 5 dotted lines in said figure showing the method of laying out the work to save stock. In cutting the collars said strip or sheet is placed on a table or platen, (not shown,) in which the bed die is set, and is fed to the dies intermittently, 10 being moved from right to left about the length of one collar at a time, and secured to the table while at rest by pins, (not shown,) which pass upwardly through holes 29 in the paper, these holes being so disposed as to come in the 15 waste pieces 34 between the ends of the collars along one edge of the strip or sheet. In order to form the ends of the collar-bands properly, or to have them turn upwardly, as shown in Fig. 1, when collars are cut in this 20 manner, a small triangular waste piece, 35, is necessarily left adhering to the center of the collar-flap of each collar in the next succeeding row or series of collars, these pieces being trimmed off by the auxiliary dies *p* 25 *j* in advance of the main dies A C. For instance, in Fig. 1 the piece marked 35 on the extreme outer edge of the strip or sheet E will be removed at the next advance of said strip to finish the collar J and cut the first section 30 or half of the collar K. The waste piece 34 is connected with the piece 35 by the narrow strip of paper 39, which comes between the ends of the bands of the collars, and the piece 34, unless separated therefrom, will be 35 dragged along with the strip or sheet E as the same is fed forward over the table, and therefore interfere with the work. It has, however, been difficult to separate these pieces at the right time and in a perfect manner 40 without greatly complicating the machinery or wasting stock on account of the narrow space between the ends of the bands and the liability of interfering with the cutting-edges of the dies at that point, and also with the 45 working of the clearer. To obviate this difficulty I make use of the cutter 25 on the die *k*, and construct the clearer *f* with the notch 27 for receiving said cutter, the notch having cutting-edges around its closed sides, so that as 50 the upper die, A, descends the cutter 25 will separate the pieces 34 and 35 by bisecting the narrow strip 39 before the clearer is depressed by the die *h* or the other cutting-edges of the dies are brought into operation. The cutting-edges of the dies *h k p* stand about an inch and 55 one-fourth from the face of the stock B, and the point of the cutter 25 about an inch and three-eighths from said stock.

It has been usual, when cutting a series of 60 paper or cloth-faced paper collars "end to end" from a strip or sheet, to "die" the stock out into narrow strips, as shown in Fig. 6, and then cut it up into collars, the first process forming the side edges of the bands and flaps, doing the creasing and embossing, and punching the center button-holes, and the second punching the end button-holes and removing the pieces 34

and 35, thereby cutting the strip up into collars.

My improvement enables the collars to be 70 cut directly from the side or edge of the sheet of paper by a single process, thereby greatly reducing the cost of manufacture, and avoiding the liability of soiling or injuring the stock by too-frequent handling.

It will be observed that one of the distinguishing features of my improved die consists in so constructing and arranging the parts as to 75 cut one-half each of two collars conjointly.

For convenience of reference, all of the parts 80 attached to the face of the holder B, except the die *p* and punches *e e*, are denominated the "die A," and all of the parts attached to the face of the bed D, except the dies *t j* and clearer *f*, are denominated the "die C."

It will be understood that the bed D is to be 85 properly mounted in a table or platen, and the follower and dies used with a suitable press and operative mechanism.

As I propose to make the process of cutting or manufacturing collars substantially as 90 described the subject-matter of other Letters Patent, (for which I have filed an application under date of June 9, 1885, Serial No. 168,192,) I do not claim the same herein, this applica- 95 tion being confined to the dies.

Having thus explained my invention, what I claim is—

1. In a lower or bed die for cutting paper or cloth-faced paper collars, the combination 100 of two cutters, each adapted, in conjunction with a suitable upper die, to cut one-half of a collar, said cutters being arranged substantially as described, so that the parts which cut the ends of the collar band and flap will be in juxtaposition, suitable creasers and stitch-em-bossers for each of the halves of the collars being cut by said cutters, and a clearer, all constructed, combined, and arranged to operate substantially as set forth.

2. In an upper die for cutting paper or cloth-faced paper collars, the combination of 105 two cutters, each adapted, in conjunction with a suitable lower die, to cut one-half of a collar, said cutters being so arranged that the 110 cutters which cut the ends of the collar band and flap will be in juxtaposition, suitable creasers and a clearer for said cutters, and a die adapted, in conjunction with a suitable lower die, to cut out the waste pieces upon the ends 120 of the bands and flaps, substantially as described.

3. In a die for cutting paper or cloth-faced paper collars, the cutter 25, in combination with the die *k*, the clearer *f*, having the notch 125 27, and springs *g*, substantially as and for the purpose specified.

4. In a die for cutting the halves of two paper or cloth-faced paper collars, the die *h*, embossers *l*, creasers *n*, punches *e e*, and die *k*, 130 constructed, combined, and arranged to complete the formation of said halves at one operation, substantially as described.

5. In a die for cutting paper or cloth-faced pa-

per collars, the dies *m*, creasers *b*, embossers *d*, said creasers and embossers acting on the parts of the collars cut out, and the clearer *f*, provided with the notch 27, all said parts 5 being constructed, combined, and arranged to operate substantially as set forth.

6. In a die for cutting out and completing the formation of the halves of two paper or cloth-faced paper collars whose ends are in 10 juxtaposition, the combination, with the dies A C, of the auxiliary dies *p j*, adapted to cut off the waste piece between the ends of the bands of the two halves of collars being cut

out, substantially as and for the purpose set forth.

7. In a die for cutting paper or cloth-faced paper collars, the dies A C *j p t*, punches *q e*, holder B, and bed D, constructed, combined, and arranged to cut out and complete the formation of the two halves of two different collars whose ends are in juxtaposition, substantially as described.

ROBERT BUTTERWORTH.
